[57] ABSTRACT

A cutter device for sheet material has a manually guidable cylindrical housing formed with a column at the base of which is supporting wheel means and a fixed blade. A reciprocating or rotary blade cooperates with the fixed blade to cut sheet material. First gear means operatively interconnect the wheel means and movable blade. A generator in the housing operatively connected mechanically to the first gear means is electrically connected to lamp means to illuminate the blades while the wheel means turns and the movable blade is moved. A motor can be provided in the housing to drive the generator, gear means, movable blade and wheel means. The wheel means may include one or two wheels.

CUTTER DEVICE WITH ILLUMINATED CUTTING BLADE

This invention concerns a manually guided cutter device for sheet material adapted to roll along a surface and move a cutting blade.

Cutter devices of the type mentioned have been known heretofore, but these generally have employed an electric motor to drive the cutting blade. Also they have generally lacked illuminating means for the cutting blade.

The present invention involves a cutter device of greater versatility than prior cutter devices of the hand guided rolling type. In the present invention manually applied power rolls the device along a cutting surface and effects moving of a cutting blade to cut sheet material on the cutting surface. The sheet material can be cloth, plastic, paper, cardboard, metal foil, etc. The cutting blade can be mechanically arranged to reciprocate or alternatively it can be a rotary blade. An electrical generator in the device energizes an illuminating lamp while the device rolls along the cutting surface and is mechanically coupled to a wheel or wheels supporting the device. Thus no external source of electric power is required. If desired, an electric motor can also be provided in the device to drive the generator, movable blade and supporting wheel or wheels. A flywheel on the drive shaft of the generator stabilizes motion of the blade, wheels and rotor of the generator. The provision of a generator for the illuminating lamp renders the lamp independent of any other source of electric power and makes it possible to use a low voltage lamp of high intensity.

Other and further features, objects and advantages of the invention will become apparent from the following detailed description taken together with the accompanying drawings, wherein:

FIG. 1 is a perspective view of a first cutter device embodying the invention.

FIG. 2 is a front end elevational view of the cutter device of FIG. 1.

FIG. 3 is an enlarged vertical longitudinal sectional view taken on line 3—3 of FIG. 1.

FIG. 4 is a further enlarged fragmentary cross sectional view taken on line 4—4 of FIG. 3.

FIG. 5, 6 and 7 are diagrams illustrating the cam drive of the movable cutter blade employed in the cutter device.

FIG. 8 is a perspective view of a second cutter device embodying the invention.

FIG. 9 is an enlarged perspective view of a fixed blade employed in the second cutter device.

FIG. 10 is a cross sectional view taken on line 10—10 of FIG. 9.

FIG. 11 is an enlarged fragmentary longitudinal sectional view taken on line 11—11 of FIG. 8.

FIG. 12 is an enlarged exploded perspective view of parts of a slip clutch employed in the second cutter device.

FIG. 13 is a perspective view of a third cutter device.

FIG. 14 is an end elevational view of the third cutter device.

FIG. 15 is an enlarged fragmentary side elevational view partially in section of third cutter device taken on line 15—15 of FIG. 13.

FIG. 16 is a fragmentary cross sectional view taken on line 16—16 of FIG. 15.

FIG. 17 is a perspective view of a fourth cutter device.

FIG. 18 is an end elevational view of the fourth cutter device.

FIG. 19 is an enlarged vertical longitudinal sectional view taken on line 19—19 of FIG. 18.

FIG. 20 is an enlarged fragmentary cross sectional view taken on line 20—20 of FIG. 17.

FIG. 21 is an enlarged side view of the cutter blades employed in the fourth cutter device.

FIG. 22 is a perspective view of a composite gear employed in the fourth cutter device.

Referring first to FIGS. 1—4, there is shown a first cutter device 25 comprising a generally cylindrical housing 26 formed by two shells held together by screws 28, 29. At the rear end of the housing is a small dynamo or generator 30 held in place by screws 32. Inside the housing are transversely extending partitions 33, 34, 35 and 36. The device rolls along a flat surface S cutting sheet material (not shown) on this surface. The housing is supported at its front end by a hollow column 38 defined by opposing lateral walls 40, 42 depending from the housing. Wall 40 is held in place by screws 43 while wall 42 is integral with the housing.

A cross shaft 44 extends transversely of the column and supports two wheels 46 in axially aligned disposition on opposite sides of the column. The housing is held in axially horizontal position by one hand of an operator (not shown) grasping the rear end of the housing. Wheels 46 have rubber tires 48 to insure traction when the wheels roll along a smooth surface. On shaft 44 is a worm wheel 50 which drives an axially vertical worm 52. Worm shaft 54 is rotatably journaled in bearing 56 in the column. At the upper end of shaft 54 is a horizontal bevel gear 58 meshed with an axially horizontal smaller bevel gear 60 carried by a short shaft 62 journaled in partitions 34 and 35. Shaft 62 carried a massive flywheel 64 and two spur gears 66, 68 on opposite sides of the flywheel between partitions 34 and 35. Gear 66 is meshed with a small pinion gear 70 at the rear end of a shaft 72 journaled in partitions 35, 36. Pinion gear 74 at the front end of shaft 72 is meshed with a crank gear 75 journaled in partition 36. Crank 76 is engaged with the crank gear and its forwardly extending crank arm 77 engages eye 78 at the upper end of slide bar 79. This bar has a slot 80 through which extend guide pins 81 in column 28 to guide bar 79 to reciprocate longitudinally. The lower end of bar 79 is formed with integral cutter blade 82. Blade 82 moves in a slot 83 in the front wall of column 28. By the arrangement described, the cutter blade 82 is caused to move up and down with to intersect vertical fixed cutter blade 84 secured by screws 85 in a slot at the bottom of column 28.

Spur gear 68 drives a smaller pinion gear 88 secured to the end of a short shaft 90 journaled in partitions 33, 34. Shaft 90 carries a larger spur gear 92 which is meshed with a smaller pinion gear 94 at the front end of shaft 95 of the dynamo 30. When the dynamo's rotor 96 is driven, electric voltage is generated and an electric current flows via wire cable 98 to a lamp socket 99 supporting lamp bulb 100 at the front end of the housing. The lamp bulb is disposed in a hood 102 formed at the front end of the housing. The hood has an internal reflecting surface 104 and is open at the bottom. The lamp bulb is lighted by electric current provided by the

dynamo when it is operating to illuminate the cloth or other sheet material being cut between blades 82, 84.

FIGS. 5, 6 and 7 show the reciprocating motion of bar 79 and cutter blade 82 caused by cranking motion of crank 76 when crank gear 75 rotates. As gear 75 is rotated counterclockwise by gear 74, crank 76 swings from side to side while bar 59 and blade 82 reciprocate up and down.

It will now be apparent that as the cutting device is rolled along surface S on which is sheet material to be cut engaged between blades 82, 84, the reciprocating blade 82 will cut the material. At the same time the rotor 96 of the dynamo will be driven to keep lamp 100 illuminated. At all times while the cutting device is in operation and rolling along a surface, rotation of wheels 46 effects the cutting action of the blades and illumination of the cutting line of the material. Flywheel 64 helps stabilize rotation of rotor 96 and reciprocation of blade 82.

The cutting device 25 is entirely manually operated. The manual power applied in moving the cutting device along surface S effects both material cutting and illumination of the material being cut. FIGS. 8-12 show another cutter device 25A which makes it possible to operate the device selectively by manually applied power or electric power supplied from an external source. Parts corresponding to those of cutter device 25 are identically numbered.

In device 25A a socket 110 is provided at one side of the housing 26a to receive plug 112 connected to cable 114 which provides electric power from any convenient source. An electric motor 116 inside housing 26a at its rear end is driven by electric power applied via socket 110 connected to motor 116. Motor 116 drives shaft 94a of dynamo 30a via a slip clutch assembly 125. This assembly as best shown in FIGS. 11 and 12 includes a rear drive disk 126 attached to shaft 128 of the motor. This disk has a stepped face which engages the stepped face of driven front clutch disk 130. Disk 130 is carried by shaft 94a at the rear end of rotor 96a of the dynamo. A coil spring 132 on shaft 94a urges the stepped faces into clutch contact with each other. In the event that flywheel 64 shown in FIG. 3 should tend to overrun the motor 116, the clutch will slip as steps 130' slip past steps 126'. A material guide and presser foot 140 is provided at the lower edge of fixed blade 84a and is integral therewith; see FIGS. 8-10.

Cutter device 25A can be operated by manually applied power in the same manner as described in connection with cutter device 25. When wheels 46 roll along the surface on which is supported material being cut, the cutter blade 82 is reciprocated up and down. In addition, the lamp 100 in hood 102 is lighted. If electric power is provided from an external source via socket 110, the motor 116 will drive the wheels 46 via the gear train shown in FIG. 3 and the device will move along the material being cut. In addition, the dynamo 30a will provide electrical voltage for illuminating the lamp. When the motor drives the cutter device, the hand of the operator grasping the housing 26a will guide movement of the device while the material is being cut.

Cutter device 25B shown in FIGS. 13-16 has only a single wheel 46' supporting the device at the bottom of column 38'. Other parts corresponding to those of

cutter devices 25 and 25A are identically numbered. The single wheel rotatably mounted between walls 40 and 42 at the bottom of the column is carried by shaft 44 which also carries a gear 150. This gear rotates with wheel 46' and drives a worm wheel 50' meshed with worm 52 at the bottom end of worm shaft 54. Other parts of the mechanical drive for vertically reciprocating bar 79 and blade 82 are the same as described above in connection with device 25. Device 25B provides an advantage of somewhat greater maneuverability since it only has one wheel. However for heavier duty work a device with two supporting wheels such as employed by devices 25 and 25A may be preferred.

Cutter device 25C shown in FIGS. 17-21, has a circular rotary cutter blade 200 rotatably supported by a foot 202 at the bottom of hollow, vertical column 204. The foot has a horizontal flange 206 integral with the column. The bottom portion of the foot is attached to flange 206. A shaft 208 extends across the foot rotatably supporting blade 200. Shaft 208 also carries a gear 210 meshed with end portions 212b of a composite gear 212 at the bottom of the column; see FIGS. 19, 20, 22. Gear 212 is mounted on a shaft 214, and is driven by gears 216 on shaft 218. Shaft 218 also carries rollers or wheels 220. These wheels rotate when the device is rolled along surface S. Gears 216 rotate gears 212 and this rotates gear 210 and rotary blade 200. The blade cooperates with fixed blade 84 carried by foot 202 in cutting the material on surface S.

Column 204 is integral with housing 225 which extends axially horizontal and is manually supported at its rear end when the device is in operation. The center section 212a of gear 212 drives worm 230 at the base of axially vertical shaft 232 in column 204. At the upper end of shaft 232 is a large bevel gear 234 meshed with a bevel gear 236 at the front end of shaft 238. Shaft 238 is axially horizontal and carries a massive flywheel 240. Dynamo or generator 242 is coupled to shaft 238 by coupling 244. Wire cable 246 leading from the generator extends through a passage 248 in the housing wall and terminates at socket 250 in hood 252 at the front end of the housing. Lamp bulb 100' in socket 250 is energized when the generator 242 is running and illuminates the cutting line of material at rotary blade 200. By the arrangement described, when the device 25C is moved along a sheet of material to be cut, rotary cutting blade 210 turns and lamp 100' is illuminated.

If desired, a single roller can be employed instead of two rollers 220. Also a motor 260 can be provided at the rear end of the casing. The motor will be coupled to the generator by coupling 261. The motor can be energized by connecting plug 112 at the end of power supply cable 114 to socket 262 at the rear end of the housing. The motor is connected to socket 262. The motor is held in the removable screw cap 264 at the rear end of housing 225 by screws 266. When the motor is operating it will drive the generator 242 to light lamp 100' and will also drive rotary blade 200 and rollers 220 via the gear train described above.

In all forms of the invention described above, hand movement of the cutter device over a cutting surface reciprocates or turns the cutting blade and energizes an illuminating lamp for the cutting line by means of an internal generator. In addition, provision of an internal motor optionally drives the generator to light the lamp

and drives a supporting wheel or wheels via a gear train. The motor also drives a rotary or reciprocating cutting blade.

While a limited number of embodiments of the invention have been illustrated and described, it will be apparent that many variations and modifications are possible without departing from the spirit and scope of the invention as defined in the appended claims.

What is claimed is:

1. A cutter device for sheet material, comprising a generally cylindrical axially horizontal housing which can be grasped manually at its rear end; a vertical column at the front end of the housing extending radially therefrom; wheel means rotatably supported at the bottom free end of the column for supporting the housing while said wheel means rolls over a surface; a fixed blade carried by said column at its bottom free end; a movable blade carried by the column; gear means operatively interconnecting said wheel and movable blade for moving the same to cut material on said surface when said wheel means rolls over said surface; an electrical generator in said housing; other gear means operatively interconnecting the first named gear means for driving said generator; and lamp means at the front end of the housing disposed to illuminate the cutting blade and material cut thereby; and electrical conductor means connecting said generator to said lamp means to energize the same while said wheel means rolls over said surface.

2. A cutter device as defined in claim 1, wherein said

movable blade is carried by a bar slidably mounted in said column and arranged to reciprocate so that the movable blade reciprocates with respect to the fixed blade.

3. A cutter device as defined in claim 1, further comprising an electric motor in the housing coupled to the generator to drive the same when electric power is supplied to the motor for energizing said lamp means and for turning said wheel means and moving the movable blade via the first named and other gear means.

4. A cutter device as defined in claim 3, wherein said movable blade is carried by a bar slidably mounted in said column and arranged to reciprocate so that the movable blade reciprocates with respect to the fixed blade.

5. A cutter device as defined in claim 3, wherein said movable blade is a circular rotatable blade.

6. A cutter device as defined in claim 3, further comprising a material guide member integral with the fixed blade and extending laterally thereof.

7. A cutter device as defined in claim 4, further comprising crank means operatively interconnecting said bar and first named gear means to cause said bar and movable blade to reciprocate.

8. A cutter device as defined in claim 1, wherein said wheel means comprises two wheels at opposite sides of said column.

9. A cutter device as defined in claim 1, wherein said wheel means comprises a single wheel.
